UNITED STATES PATENT OFFICE.

ALBERT C. GRUNWALD, OF MAYWOOD, ILLINOIS, ASSIGNOR, BY MESNE ASSIGNMENTS, TO THE AUTOMATIC RECORDING SAFE COMPANY, OF CHICAGO, ILLINOIS, A CORPORATION OF ILLINOIS.

DESIGN FOR A CLOCK-BANK CASE.

50,719.

Specification for Design.

Patented May 8, 1917.

Application filed April 22, 1915. Serial No. 23,117. Term of patent 7 years.

To all whom it may concern:

Be it known that I, ALBERT C. GRUNWALD, a citizen of the United States, residing at Maywood, in the county of Cook and State of Illinois, have invented a new, original, and ornamental Design for a Clock-Bank Case, of which the following is a specification, reference being had to the accompanying drawing, forming a part hereof.

Figure 1 is a perspective view, and Fig. 2 is a front elevational view of a clock-bank case in accordance with my new design.

Copies of this patent may be obtained for five cents each, by addressing the "Commissioner of Patents, Washington, D. C."

The design is intended for use in a combination savings-bank and clock; and while the design preferably is of the form shown, such variations as may be made without materially modifying the design are contemplated.

I claim:

The ornamental design for a clock-bank case, as shown.

ALBERT C. GRUNWALD.
